US00D622276S

(12) **United States Design Patent**
Tran et al.

(10) **Patent No.:** US D622,276 S
(45) **Date of Patent:** ** Aug. 24, 2010

(54) **HEALTH RECORD STORAGE DEVICE**

(76) Inventors: **Tuyen T. Tran**, 4390 Clearwater Way # 3102, Lexington, KY (US) 40515; **Thuy Lynh N. Tran**, 4390 Clearwater Way # 3102, Lexington, KY (US) 40515

(**) Term: **14 Years**

(21) Appl. No.: **29/316,828**

(22) Filed: **Nov. 6, 2009**

(51) **LOC (9) Cl.** **14-02**

(52) **U.S. Cl.** **D14/480.1**

(58) **Field of Classification Search** D14/356, D14/411, 433, 435.1, 436, 137, 155, 167, D14/168, 203.1–203.8, 240, 242, 299, 480.1–480.7, D14/484.1; D3/201, 273; D13/107, 108, D13/149, 184; 710/300, 301; 439/131, 135–147; 361/679.31, 679.33, 679.4, 752; 711/100, 711/115

(57) **CLAIM**

The ornamental design for a health record storage device, as shown and described.

DESCRIPTION

FIG. 1 is a perspective view of health record storage device of this invention.

FIG. 2 is a top plan view of the health record storage device shown in FIG. 1.

FIG. 3 is a right side elevational view of the health record storage device shown in FIG. 1.

FIG. 4 is a bottom plan view of the health record storage device shown in FIG. 1.

FIG. 5 is a left side elevational view of the health record storage device shown in FIG. 1.

FIG. 6 is a front end elevational view of the health record storage device shown in FIG. 1; and,

FIG. 7 is a rear end elevational view of the health record storage device shown in FIG. 1.
